UNITED STATES PATENT OFFICE.

REGINALD A. FESSENDEN, OF BROOKLINE, MASSACHUSETTS, ASSIGNOR TO SUBMARINE SIGNAL COMPANY, OF PORTLAND, MAINE, A CORPORATION OF MAINE.

METHOD AND APPARATUS FOR SUBMARINE SIGNALING.

1,348,827.

Specification of Letters Patent.

Patented Aug. 3, 1920.

Application filed November 29, 1918. Serial No. 264,607.

To all whom it may concern:

Be it known that I, REGINALD A. FESSENDEN, of Brookline, in the county of Norfolk and State of Massachusetts, a citizen of the 5 United States, have invented new and useful Improvements in Methods and Apparatus for Submarine Signaling, of which the following is the specification.

My invention relates to submarine signaling, and the generation, detection, and utilization of impulses in fluid media, and more especially to methods of mounting submarine sound producers and detectors.

My invention has for its object increased 15 efficiency in submarine impulse production and submarine impulse detection, and more particularly greater efficiency in sending and receiving directly ahead and astern, and greater freedom from disturbance by undesired noises, for example, ship noises and water noises.

Figures 1 and 2 accompanying this application show particularly diagrammatical means suitable for carrying out my invention.

I have found that by locating the apparatus for generating and receiving submarine impulses within the area formed by the downward prolongation of the ship's side 30 (shown by the dotted line 12-13 in Fig. 1), the outward prolongation of the ship's bottom (shown by the dotted line 13-14 in Fig. 1) and the rounded portion of the ship's skin lying between the ship's side and the 35 ship's bottom (shown by the full line 12-14 in Fig. 1), this increased efficiency can be obtained.

The left hand side of Fig. 1 shows one suitable arrangement, where 11 is the cross 40 section of the ship, 15 is a bilge keel, placed in the area above referred to, and 16 is any suitable generator of submarine impulses, for example, applicant's oscillator, described in U. S. Patent No. 1,167,366, dated Jan. 45 4, 1916.

The right hand side of Fig. 1 and Fig. 2 shows another suitable arrangement, where a tube, 17, is held in a ring of rubber or similar material, 26, and this again is held in 50 a ring of steel or similar material, 25,

The steel ring, 25, is held, preferably in a slanting position with reference to the ship's skin, by means of the three struts, 18, 19, 20, the lower ends of these struts being fastened to the ship's skin.

The arrangement is shown from the side in Fig. 2.

The tube, 17, as shown in the left hand side of Fig. 2, has its outer end closed by a rubber cork or diaphragm, 21, to which is attached any suitable receiving device, for example, a number of nickel rod detectors. One of these rods is shown at 22, having its inner end attached to a weight, 27, and surrounded by a coil, 28, whose terminals, 23, 24, are brought inside of the ship's skin as shown.

This method and construction have a number of important advantages. The apparatus placed in this position is free from all danger of injury when the ship lies alongside a dock, or grounds on a shore. Again, apparatus so arranged and located is capable of sending and receiving impulses from ahead and astern, as well as broad- 75 side on, since it is not in the shadow of the bow or the stern of the ship when receiving from a sound source at a considerable distance ahead or astern, and is nevertheless in the sound shadow of the propeller 80 noises, and may be shadowed if desired by means of sound screens from internal hull vibrations or engine vibrations, such a sound screen being shown at 30 in Fig. 1.

It has also the advantage that it is much 85 less affected by water noises produced by the relative motion between the ship's skin and the surrounding water.

What I claim is:

In a submarine signaling system, the combination of means for submarine signaling and a ship's hull, said means being within the area bounded by the vertical prolongation of the ship's side, the outward prolongation of the ship's bottom, and the line joining the lower extremity of the ship's side to the outward extremity of the ship's bottom.

REGINALD A. FESSENDEN,
